PUMP LUBRICATING SYSTEM

Merton T. Archer, Pittsburgh, Pa., assignor to
 The National Supply Company, Toledo, Ohio,
 a corporation of Ohio

Application April 1, 1929. Serial No. 351,698

8 Claims. (Cl. 184—11)

This invention relates to lubricating systems designed particularly for pumps, but it is applicable to other systems where eccentrics are employed.

5 It is the principal object of this invention to provide means whereby eccentrics positioned on opposite sides of a gear wheel may be thoroughly lubricated by means of lubricant carried up by the gear wheel and distributed laterally and allowed 10 to fall upon specially formed surfaces for conveying the lubricant to the bearing surfaces between the eccentrics and the bushings or linings carried by the eccentric straps. Further objects appear hereinafter.

15 Referring to the accompanying drawings, Fig. 1 is a vertical section of the gear casing and of the oil distributing parts attached to the casing, the gear wheel, the eccentrics and the bearings for the gear wheel shaft being shown in elevation; Fig. 2, a vertical section on the line 2—2 on Fig. 1, parts being shown in elevation and broken away; Fig. 3, a section on the line 3—3 on Fig. 2; Fig. 4, a perspective view with parts being in vertical section and broken away, the vertical 25 section extending from one side of the figure to the other, being in the same plane as the section shown at the top of Fig. 1; Fig. 5, a section on the line 5—5 on Fig. 4; Fig. 6, a fragmentary view showing in perspective a portion of one of the 30 eccentric straps, parts being shown in the vertical section; and Fig. 7, a section on the line 7—7 on Fig. 6.

The casing comprises a main member 1 and the cover member 2 which is secured to the main member by the bolts 3. Bearings 4 in the sides 35 of the casing support the ends of the shaft 5 which carries the large spur gear wheel 6 and also the eccentrics 7 and 8, one on each side of the gear wheel 6. The bottom of the casing 1 has a sump or reservoir 9 to contain lubricant and 40 into which the gear wheel 6 dips.

The cover 2 supports the vertical baffle 10 which is vertically over the gear wheel 6 and is parallel with the periphery of the gear wheel. Each side 45 of the baffle carries an upwardly-open trough 11 extending from one end of the baffle to the other. At each side of the gear wheel 6 and pendent from the cover 2 is a flange 12 parallel with the sides of the gear wheel. These flanges cover the 50 ends of the troughs 11 and have inclined passages 13 therein to conduct lubricant from the troughs down into the spouts 14 projecting laterally from the outer faces of the flanges. The spouts are preferably arranged directly over the center line 55 of the shaft 5 and so that lubricant dropping

from them falls upon the eccentric straps as hereinafter described. The spouts are preferably of small width, their end walls communicating with horizontal passages 15 in the walls of the flanges below the passages 13. The passages 15 extend for some distance at each side of each spout 14 and have a long narrow opening 16 facing the space between the top of the gear wheel and the bottom of the baffle 10 and the troughs 11. These passages 15 extend downwardly and 60 outwardly and deliver into the spouts some of the lubricant carried up by the gear wheel. 65

The two eccentric structures are identical. Accordingly, only that relating to the eccentric 8 will be described. The eccentric strap comprises 70 two arcuate members 17 and 18 provided respectively with the arcuate bushings 19 and 20 which conform to the periphery of the eccentric 8 and form substantially a complete circle and bears upon the periphery of the eccentric 8. The strap members 17 and 18 have their ends fastened together by bolts 21, the opposing ends of the said members being preferably in a vertical plane which includes the center of the eccentric. The two opposing ends of the members 17 and 18 at 75 the upper side of the eccentric are formed into two heads 22 and 23, each having upwardly-open reservoirs 24. The head 22 is shown in Fig. 6 with two reservoirs, while the head 23 is shown in Fig. 2 with only one reservoir 24, but it is to be 80 understood that the head 23 has the same construction as the head 22 which has, therefore, on its upper face two reservoirs 24. The construction shown in the head 22 will be described, it being understood that the same description will 85 apply to the head 23. Each reservoir 24 feeds lubricant downwardly through a passage 25 into an inclined passage 26 in the bushing 19 and thence into the space between the two bushings 19 and 20, the lubricant flowing downwardly between the opposing ends of the bushings 19 and 20 and into contact with the periphery of the eccentric 8. The opposing ends of the said bushings are bevelled slightly below to facilitate the 90 flow of the lubricant. 95

The upper faces of the members 17 and 18 are channel-shaped with the channels 27 and 28 opening outwardly. These channels extend from the ends of the heads 22 and 23 downwardly to the ledges 29 and 30 respectively. Lubricant 100 passing down the channels 27 and 28 reaches the periphery of the eccentric 8 through the passages 31 and 32, a portion of each of these passages being through a hollow dowel 33 lying partly in each strap member and its companion bushing. 110

These dowels prevent the movement of the bushings in the strap members and at the same time furnish a passage for the lubricant.

The strap member 18 is provided with a connecting rod 34, it being understood that the corresponding strap member for the eccentric 7 has a corresponding rod. In the case of the pump the connecting rods would be connected to the usual cross-head to which the piston rods for the pump 10 pistons would be attached.

As the gear wheel rotates in one direction or the other lubricant will be centrifugally thrown into one of the troughs 11 from which it will flow into the spouts 14. At the same time some of the oil 15 carried up by the gear wheel will flow through the opening 16 and into the passages 15 and thence into the spouts. The lubricant falling from the spouts will drop upon the eccentrics, some of the lubricant falling into the reservoirs 20 24 and some into the channels 27 and 28, the lubricant passing into the eccentric bearings in a manner already described.

I claim:—

1. In a lubricating system, a casing, a shaft 25 having bearings therein, a gear wheel and an eccentric on each side thereof rotatable with the shaft, a trough integral with the casing and positioned above the gear wheel and spaced therefrom and adapted to receive lubricant centrifugally from the gear wheel, a spout at each end of the trough and beyond the sides of the gear wheel to receive lubricant from the trough, means for receiving lubricant from the trough and conveying it to the bearing surfaces of the eccentric, 35 vertical flanges adjacent to each side of the gear wheel and pendent from the trough, and passages below the trough and in the flanges for conveying lubricant from the upper part of the gear wheel to the spouts.

2. In a lubricating system, a gear wheel, an eccentric rotating therewith and adjacent thereto, a strap about the eccentric, a bushing between the eccentric and the strap and bearing on the periphery of the eccentric, a head on the upper 45 side of the strap, a lubricant reservoir on the head, means to deliver lubricant from the reservoir to the periphery of the eccentric, lubricant receiving and conducting channels in the strap at opposite sides of the head, means to lead lubricant from the channels to the said periphery, and means for receiving lubricant from the upper part of the gear wheel and directing it into the reservoir and the channels.

3. In a lubricating system, a gear wheel, an eccentric rotating therewith and adjacent thereto, a strap about the eccentric, a bushing between the eccentric and the strap and bearing on the periphery of the eccentric, a head on the upper side of the strap, a lubricant reservoir on the 55 head, means to deliver lubricant from the reservoir to the periphery of the eccentric, lubricant receiving and conducting channels in the strap at opposite sides of the head, means to lead lubricant from the channels to the said periphery, and means for receiving lubricant from the upper part of the gear wheel and directing it into the reservoir and the channels, a portion of the last named means consisting of hollow dowels connecting each strap to the adjacent bushing.

4. A structure vertically over the center of a wheel and having at its sides and integral therewith pendent flanges opposite the upper side portions of the wheel, spouts carried by the outer

sides of the flanges, there being openings in the flanges for oil to pass laterally from the upper portion of the wheel, a trough in that portion of the said structure which is over the wheel to receive oil centrifugally therefrom and passages to lead oil from the trough to the spouts, and bearings to which the oil is supplied from the said spouts.

5. A structure vertically over the center of a wheel and having at its sides and integral therewith pendent flanges opposite the upper side portions of the wheel, spouts carried by the outer sides of the flanges, there being openings in the flanges for oil to pass laterally from the upper portion of the wheel, two troughs in that portion of the structure which is over the wheel, the troughs being arranged, one to receive oil centrifugally from the wheel when it rotates in one direction and the other to receive oil centrifugally from the wheel when it rotates in the opposite direction, passages to lead oil from the trough to the spouts, and bearings to which the oil is supplied from the said spouts.

6. A casing, a horizontal rotary shaft extending through the same, a gear wheel in the casing 100 and on the shaft, eccentrics in the casing and at opposite sides of the wheel, a top cover for the casing, and an oil-receiving and distributing structure carried by the under side of the cover, the said structure being located vertically over 105 the center of the wheel and having a spout arranged laterally of the wheel to feed oil to the eccentrics, a trough arranged to receive oil centrifugally from the wheel, means to lead oil from the trough to the spouts, depending flanges at the 110 sides of the wheel, and passages in the flanges to carry the oil from the sides of the wheel to the spouts.

7. A casing, a horizontal rotary shaft extending through the same, a gear wheel in the casing 115 and on the shaft, eccentrics in the casing and at opposite sides of the wheel, a top cover for the casing, and an oil-receiving and distributing structure carried by the under side of the cover, the said structure being located vertically over 120 the center of the wheel and having a spout arranged laterally of the wheel to feed oil to the eccentrics, a trough arranged to receive oil centrifugally from the wheel when it rotates in one direction, a trough arranged to receive oil centrifugally from the wheel when it rotates in the other direction, means to lead oil from the trough to the spouts, depending flanges at the sides of the wheel, and passages in the flanges to carry the oil from the sides of the wheel to the spouts.

8. In a lubricating system, a casing including a removable cover on its upper side, a gear wheel within the casing and below the cover, eccentrics adjacent to each side of the gear wheel and rotatable with the gear wheel and requiring lubrication, a baffle directly over the center of the gear wheel and arranged transversely thereof and integral with the cover, a trough free from the gear wheel and carried by the baffle at each side thereof and parallel therewith, one arranged to receive lubricant centrifugally of the gear wheel when the gear wheel rotates in one direction and the other arranged to receive lubricant when the gear wheel rotates in the other direction, and means conveying the lubricant from each trough to the eccentrics.

MERTON T. ARCHER.
